UNITED STATES PATENT OFFICE.

JOSEPH A. FREUND, OF NEWTONVILLE, MASSACHUSETTS, ASSIGNOR TO THE KEY-STONE WATCH CASE COMPANY, OF PHILADELPHIA, PENNSYLVANIA, A CORPORATION OF PENNSYLVANIA.

WATCH-WINDING DEVICE.

Application filed March 18, 1919, Serial No. 283,324. Renewed February 3, 1921. Serial No. 442,324.

To all whom it may concern:

Be it known that I, JOSEPH A. FREUND, a citizen of the United States, and resident of Newtonville, county of Middlesex, and 5 State of Massachusetts, have made a certain new and useful Invention Relating to Watch-Winding Devices, of which the following is a specification, taken in connection with the accompanying drawing, which 10 forms part of the same.

This invention relates especially to stem winding devices for watches in which the dial plate is of thick heavy construction so as to comprise a large part of the thickness of the watch movement, the bridge members which are preferably in the form of flat plates of substantially uniform thickness in the parts which are in contact with the dial plate being advantageously maintained in alignment therewith by steady pins which may be removably mounted in holes in the dial plate, so that these parts may be bored and jewelled from the steady pin holes as described and claimed in my 20 co-pending application, Serial No. 246,794, filed July 26, 1918, which has been patented September 27, 1921, as No. 1,392,006, of which this case is a partial continuation. The dial which may be secured to the other 25 side of the dial plate may be of approximately the same thickness as the bridge members so that the winding stem may have the desired substantially central location in the watch movement by arranging it substantially centrally with respect to the thickness of this dial plate. The hole for the stem bearing may be bored or milled out of this heavy dial plate and this hole or recess may be of such size that the winding 30 stem and its clutch and winding pinion which may be arranged wholly within the dial plate if desired, may all be inserted endwise into this hole or recess in the dial plate which greatly facilitates assembly of the parts. Furthermore the winding stem 35 may be supported at its outer end in a replaceable or interchangeable winding pinion thrust block held within the recess in the dial plate so as to form a firm and accurate stem bearing which may also be readily replaced in case of wear caused by the dirt which works in between these parts.

In the accompanying drawing showing in

a somewhat diagrammatic way illustrative embodiments of this invention,

55

Fig. 1 is a transverse central section through the watch movement.

Fig. 2 is a partial top view thereof.

Fig. 3 is a partial sectional view taken through the parts adjacent the winding 60 stem in a direction at right angles to Fig. 1; and

Fig. 4 is a similar sectional view showing a modified construction.

The use of a relatively thick and heavy 65 dial plate of this character makes it possible to secure greatly increased strength and accuracy of the stem bearings of the watch since the winding stem 24 may be mounted entirely within the thick dial plate 70 1 and practically centrally located with respect thereto as indicated. This dial plate may be formed with suitable recesses, such as 25, 27, 50, for the various parts of the watch movement and the cooperating thin 75 bridge members 2, 3, 4, may be secured to the dial plate and at the same time advantageously held in alignment therewith by steady pins, such as 32, which may have reduced or rounded ends 33 cooperating 80 with holes 11 in the various bridge members. In this way the jewel and other bearings may be brought into accurate alignment, as is seen in the case of the center bearing jewel 21 in the bridge member 3. The dial 85 10 secured in any desired way on the other side of the dial plate 1 may as indicated have a flange forced over and engaging a projecting rim portion 12 on the dial plate to assist in maintaining engagement there- 90 with.

The winding stem may have the reduced stem pivot 40 mounted in a substantially central bearing hole in the dial plate itself while the outer end of the stem beyond the 95 winding pinion 41 and clutch 34 may, if desired, be supported by a removable thrust block or bearing member 36 for this winding pinion, which may also be formed with a bearing aperture to accommodate the stem 100 adjacent the stem groove 30 for the pendant lever. This thrust bearing member may fit accurately within the thrust block recess 51 in the dial plate as indicated in Fig. 3 and be retained therein as by the locking screw 105 38 engaging a notch or recess 37 in the thrust

block which may not only be replaceable but interchangeable. Thrust bearing members of this character may in some cases be advantageously employed to regulate the depth 5 of penetration of the winding pinion 41 in the teeth of the cooperating crown gear 142 by having the central part of this thrust bearing member which cooperates with the aperture 52 for the winding pinion project 10 somewhat further downward therein, so that as indicated in Fig. 4 a projecting bearing face 56 may be formed on this thrust block, so that the winding pinion may thus be forced further inward toward the center 15 of the crown wheel and a greater degree of penetration with the teeth thereof be insured. This interchangeable thrust bearing member also has the very decided advantage that it makes completely replaceable and 20 readily renewable this important bearing where the greatest wear occurs in a watch movement, and in case this bearing wears sufficiently to become loose or objectionable it is a very simple matter to remove this 25 thrust bearing member and replace it by another of the same or slightly different character, so that if desired increased penetration of the pinion may be insured in this way to a sufficient degree to take up the 30 wear which has incidentally occurred in these meshing teeth.

This construction makes possible the formation of the recesses to accommodate the winding pinion clutch and stem pivot by a 35 single milling or boring operation, the cutter or boring tool being, if desired, formed with different diameter portions adapted to simultaneously form the hole for the stem pivot 40 and also the stepped recesses 51, 40 52, 53, for the thrust bearing member and other parts, all of these recesses thus being properly located in co-axial relation so as to ensure the proper fitting and meshing engagement of the cooperating parts. As indicated, the stem may be formed with a polygonal or square section portion 42 above 45 its pivot 40 so that the winding clutch 54 may move longitudinally thereon while rotated by this member, the clutch having a 50 recess 34 with which a resetting lever of any desired construction may cooperate so that either the teeth on this clutch are in mesh with the cooperating teeth which may be formed on the winding pinion, or the gear 55 teeth on the other end of this clutch member may when the setting lever is in the other position mesh with the interset wheel 55 to operate the hands by the usual gearing. This construction also has the advantage 60 that the winding stem clutch and winding pinion can all be inserted together with the stem and thrust bearing member through the aperture 51 in the thick dial plate which makes it correspondingly easy to remove 65 these parts for cleaning or repair without

disturbing any of the other parts of the watch movement. By having the stem located substantially centrally with respect to the thickness of the heavy dial plate the stem may readily be brought into substantially central position as regards the thickness of the entire watch movement and the dial, since the relatively thin bridges 2, 3, 4 on one side of this dial plate may be made approximately of the same thickness as the 70 dial 10 on the other side so that in the complete movement this central position of the stem may be readily maintained as indicated in Fig. 1.

This invention has been disclosed in connection with a number of illustrative forms, arrangements, proportions, materials and methods of manufacture and use, to the details of which disclosure the invention is not of course to be limited, since what is claimed 80 as new and what is desired to be secured by Letters Patent is set forth in the appended claims.

1. In watch movements, a thick dial plate, a series of cooperating relatively thin bridge 90 members removably secured to one side of said dial plate, a dial of approximately the same thickness as said bridge members secured to the other side of said dial plate, a winding stem having at one end a reduced diameter winding stem pivot and having a polygonal portion to rotate therewith the longitudinally movable clutch pinion, a winding pinion secured to said winding stem, there being a series of recesses 100 formed in said dial plate to constitute a bearing aperture for said winding stem pivot and to constitute a thrust block recess of larger diameter than said winding pinion to permit the endwise insertion of said 105 winding stem and cooperating parts into said dial plate, and a winding pinion thrust block removably secured in said thrust block recess to determine the penetration of its 110 teeth with the teeth of the cooperating crown wheel.

2. In watch movements, a thick dial plate, a winding stem having a winding stem pivot, a winding pinion secured to said winding stem, there being a series of recesses formed in said dial plate and comprising a bearing recess, and a winding stem bearing member secured in said bearing recess.

3. In watch movements, a thick dial plate, a winding stem, a winding pinion secured to said winding stem, a bearing recess of at least as large diameter as said winding pinion formed in said dial plate to permit the endwise insertion of said winding stem and winding pinion, and a bearing member secured in said recess and formed with a bearing face cooperating with said winding pinion.

JOSEPH A. FREUND.
